UNITED STATES PATENT OFFICE

CLAIR P. NOURSE, OF MILWAUKEE, WISCONSIN, ASSIGNOR TO THE MIDLAND COMPANY,
OF SOUTH MILWAUKEE, WISCONSIN, A CORPORATION OF WISCONSIN

JOINTED CLIP

Application filed May 19, 1927. Serial No. 192,705.

This invention relates to improvement in jointed clips.

Jointed clips are used for the purpose of connecting the trace of a harness to a hame and permit pivotal and swivelling movements. Heretofore clips of this character have been formed in three pieces, comprising a member connected to the trace, an intermediate member pivotally connected thereto, and an outer member pivotally connected with the intermediate member and connected with the hame.

It is one of the objects of the present invention to provide a jointed clip which is formed of but two members, requiring fewer parts than have heretofore been used for like clips and reducing the cost of manufacture.

A further object of the invention is to provide a jointed clip which can be entirely stamped from sheet steel.

A further object of the invention is to provide a jointed clip which may be swiveled and pivoted and which is also provided with means for limiting the movement of the parts with respect to each other to prevent the same from getting stuck or caught in extreme positions of movement.

A further object of the invention is to provide a jointed clip in which the hame connection is provided with an off-set portion to accommodate the collar rib and prevent undue wear.

A further object of the invention is to provide a jointed clip which is of very simple construction, is inexpensive to manufacture, is strong and durable, and is well adapted for the purpose described.

With the above and other objects in view the invention consists of the improved jointed clip, and its parts and combinations as set forth in the claim, and all equivalents thereof.

In the accompanying drawing in which the same reference characters indicate the same parts in all of the views:

Fig. 1 is a side view of the improved jointed clip connected with a trace and with a hame, parts being broken away and shown in section;

Fig. 2 is a longitudinal sectional view thereof taken on line 2—2 of Fig. 1; and

Fig. 3 is a longitudinal sectional view illustrating a modified form of clip attached to a trace and hame.

Referring now more particularly to Figs. 1 and 2 of the drawing it will appear that the numeral 5 indicates a trace engaging member which is provided with a pair of spaced trace engaging tongues 6 between which the end portion of a trace 7 extends and is rigidly secured by rivets 8. The end portion of each tongue terminates in an enlarged disc portion 9 provided with an inwardly flanged edge 9'.

The jointed clip also includes a swivel member 10 which is in the form of a doubled sheet of metal forming an inner doubled tongue portion 11 and an outer looped portion 12 in which latter portion a transverse opening 13 is provided between the thicknesses of metal and the looped portion is off-set inwardly 70 to accommodate the rib of a horse collar.

The doubled tongue portion of the swivel member is extended between the flanged edges of the disc portions of the member 6 and is pivotally connected between said disc portions by a pivot bolt or rivet 14 extended through the central depressed portions 15 of the discs and the layers of the tongue.

The swivel member 10 of the jointed clip is adapted for attachment to a hame 16' carried by a horse collar 16 of ordinary construction, the hame being provided with a hame bolt 17, and as shown the hame bolt extends through the aperture of the looped portion of the swivel member and the jointed clip 85 is free to turn on said bolt.

Pivotal or swivelling movement between the swivel member and the trace engaging member is limited by a pin 18 extended transversely through the forward portions of the disc portions and also extending through a curved slot 19 in the tongue portion of the swivel member, movement being limited by the engagement of the pin with the ends of the slot.

All parts of the jointed clip are stamped from sheet steel and limited swivelling movement is afforded by the connection of the two members as well as lateral pivotal movement of the entire clip on the hame bolt.

In the modified form of clip shown in Fig. 3 the tongue portion of the swivel member is extended exteriorly of the disc portions 9" and to permit this arrangement said disc portions are off-set inwardly from the portions 6 while the layers 11' forming the tongue of the swivel member are separated. A pivot pin 14 is extended through all of said portions, as shown. A limiting stop is provided by a pin 18 extended through all of the members and a pair of registering curved slots 19' in the disc portions.

From the foregoing description it will be seen that the improved jointed clip is of very simple and novel construction, and is well adapted for the purpose set forth.

What I claim as my invention is:

The combination with a hame having a hame bolt and a trace, of a two-piece jointed clip directly connecting the trace and hame bolt, comprising a pair of spaced apart arms, each having an attaching tongue and an enlarged disc portion, the trace being secured flatly between said tongues, and a swivel member having an inner bi-layered tongue portion extended between said disc portions and pivotally connected thereto and an integral outer inwardly offset looped portion, said hame bolt being pivotally extended through the looped portion, the tongue of the swivel member having a curved slot therein and a pin extending through the disc portions and said slot for limiting the pivotal movement of the swivel member with respect to the arms.

In testimony whereof, I affix my signature.

CLAIR P. NOURSE.
